UNITED STATES PATENT OFFICE.

SAMUEL M. FULTON, OF POMONA, CALIFORNIA.

PUMP.

SPECIFICATION forming part of Letters Patent No. 772,880, dated October 18, 1904.

Application filed November 18, 1903. Serial No. 181,695. (No model.)

To all whom it may concern:

Be it known that I, SAMUEL M. FULTON, a citizen of the United States, residing at Pomona, in the county of Los Angeles, State of California, have invented certain new and useful Improvements in Pumps, of which the following is a specification, reference being had therein to the accompanying drawings.

This invention relates to pumps, and particularly to a structure of valved piston and coöperating check-valve.

The invention has for an object to improve the construction of the valved piston so as to provide a larger and freer water-passage there-through and to furnish a structure which will sustain a heavy pressure in deep-well pumping and not become easily clogged with sand or other matter carried by the water.

A further object of the invention is to improve the construction of the valve-disks and of the piston-frame for carrying the packings and coöperating with said disks.

Another object of the invention is to provide improved means for connecting the piston to the cage of the check-valve, so that the latter may be placed in position and removed from the well-casing through the medium of the valved piston.

Other and further objects and advantages of the invention will be hereinafter set forth, and the novel features thereof defined by the appended claims.

In the drawings, Figure 1 is a central vertical section through the valved piston and check-valve. Fig. 2 is a perspective of these parts removed from the well-casing. Fig. 3 is an elevation, with parts in section, of a modification showing a double-valved piston construction. Fig. 4 is a cross-section on the line 4-4 of Fig. 3. Fig. 5 is a similar view on the line 5-5 of Fig. 3. Fig. 6 is a detail perspective of the frame for the valved piston, and Fig. 7 is a section on the line 7-7 of Fig. 2.

Like letters of reference refer to like parts in the several figures of the drawings.

The letter A designates a well-casing which may be of any suitable construction, and is provided with a cylinder-cap A', carrying at its free end a water-chamber having a valve-seat A², with which the check-valve B, carried

by the valve-cage B', is adapted to coöperate. This check-valve is slidingly mounted in a bearing B³ in the lower portion of the cage by means of the shank B⁵, and the downward movement of said shank is limited by the collar B⁴ at the upper end of the shank. The valve-cage rests at its lower end upon a shoulder A³, carried by the cylinder-cap A', while a spring packing-ring F is mounted upon the arms B⁵ of the cage. The packing F is composed of a series of segmental springs bolted to the arms B⁵ of the cage at one end F¹ and reduced in width at the opposite free end F², so as to pass behind the bolted end and between the bolts thereof to form an elastic ring. The upper portion of the cage comprises an annular portion B⁶, having at opposite points thereon radially-extending lugs B⁷, adapted to coöperate with the cage-lifting means hereinafter described.

The valved piston C is carried at the lower end of a suitable rod C' in any desired manner—for instance, by means of the stem C², threaded into the pump-rod C' and the hub C³ of the piston-frame. This hub has a series of radially-extending spokes C⁴, enlarged at their outer threaded ends C⁵. At the lower end of the piston-frame an exteriorly-threaded ring C⁶ is provided, and at the upper portion a recessed ring C⁷ is disposed and provided upon its upper surface with a valve-seat C⁸, adapted to coöperate with a valve or clapper D. The upper surface C⁹ of the hub C³ is disposed at a distance below the valve-seat C⁸ to provide the largest water-passage for the free discharge of the piston. A cushion C¹⁰ may also be provided at this point for contact with the lower end D' of the valve or clapper, if desired. The lower portion of this valve is also outwardly curved, so that the water striking the same is guided outwardly around the valve and the formation of eddies beneath the valve will be entirely prevented. The under surface of the valve is provided with a packing D³, suitably secured thereto. As shown at the lower part of Fig. 3, this form of valve may be used alone in connection with the piston; but if it be desired to secure an additional water-discharge area the valve may be provided with a series of apertures D⁴ there-

through, as shown in Fig. 1 and the upper portion of Fig. 3, which apertures are adapted to be closed by a valve-disk D⁵, slidingly mounted upon a post D⁶, extending upward from the valve D, while the upward movement of this disk D⁵ may be limited by the nut or collar D⁷, threaded upon the post D⁶. The piston-frame is provided with the usual flexible packing-rings E, which are adapted to be secured in position by means of interiorly-threaded rings E', screwed upon the periphery of the valve-spokes and adapted to clamp the lower edge of the packings E between the adjacent faces of the rings and the under face of the recessed ring C⁷ at the top of the frame. Each of the rings E is formed with the usual recess E² to permit the proper operation of the packing-rings, while the several rings are secured in position by means of the locking-ring E³, threaded upon the lower portion C⁶ of the valve-casing. When it is desired to use the valved piston for the purpose of inserting the check-valve or removing the same from the well-casing, this clamping-ring E may be provided with depending lugs E⁴, adapted to engage beneath the lugs B⁷ for the purpose of supporting the valve-cage and to be disengaged from said lugs by a partial rotation of the piston. In Fig. 3 a modified application of the invention is shown in which these hooks are omitted from the lower piston and two pistons are used, as in the double-valved piston-pump, the upper piston being provided with a main valve D and an auxiliary disk D⁵, while the lower piston is provided with a valve D, having no apertures therethrough.

In the operation of the invention it will be seen that in the rising movement of the piston the valves at the upper portion thereof close, thus carrying the body of water above the piston upward in the pumping action, while in the return movement these valves open, as shown in Figs. 1 and 2, thus providing the largest and freest water-passage through the piston to reduce the resistance to the piston to a minimum, and thus effect a pumping action requiring the least power and one particularly adapted for deep wells, where the extended length of rod is necessary. Furthermore, the construction of valve-cage shown in connection with the enlarged chamber within the cylinder-cap provides an extended water area around the check-valve, which is thus left free for operation and effectually prevented from clogging due to the presence of sand and other matter in the water. It will also be seen that the structure of valve-frame permits the assembling and disconnection of the several parts for the purposes of construction and repair in the simplest manner, thus obviating the necessity of skilled labor and producing a valved piston adapted to stand the strain of working under a heavy load and one which is both simple and economical in construction and manu-

facture. The means carried by the valved piston for connection and disconnection with the valve-cage permit the latter to be lowered into position upon its seat, when it may be released from the piston by a partial rotation thereof, and the parts may be again connected together for the purpose of removing the check-valve when desirable by a simple reversal of this operation.

It will be obvious that changes may be made in the details of construction and configuration without departing from the spirit of the invention as defined by the appended claims.

Having described my invention and set forth its merits, what I claim, and desire to secure by Letters Patent, is—

1. In a pump, a piston-frame provided upon its upper face with a bearing-seat, a hub within said frame disposed below said seat and having a valve-seat upon its upper face, radiating spokes from said hub having a threaded face at their free ends, packings secured to said face, and a valve carried by a stem from said hub and having faces in different horizontal planes to contact with said seats.

2. In a pump, a piston-frame having a valve-seat at one end, a hub within said frame of less length than the frame, radiating spokes from said hub exteriorly threaded at their free ends, a ring at the upper portion of said spokes, packings and packing-rings threaded upon said spokes, and a clamping-ring threaded upon the lower portion of said spokes to retain the packings in position.

3. In a pump, a piston-frame comprising a hub, radiating spokes therefrom exteriorly threaded at their free ends, a ring at the upper portion of said spokes, packings and packing-rings threaded upon said spokes, a clamping-ring threaded upon the lower portion of said spokes to retain the packings in position, and depending hooks carried by a ring threaded upon said spokes at the lower portion of said frame.

4. In a pump, a cylinder-cap provided with a valve-seat, a valve-cage carrying a check-valve to rest upon said seat, lifting-lugs provided at the upper portion of said valve-cage, and a valved piston provided with hooks to engage said lugs by a rotation of the piston.

5. In a pump, a cylinder-cap provided with a valve-seat, a valve-cage carrying a check-valve to rest upon said seat, lifting-lugs provided at the upper portion of said valve-cage, a valved piston provided with hooks to engage said lugs by a rotation of the piston, a water-chamber provided in said cylinder-cap above said valve-seat, and a supporting-flange for said cage at the upper portion of said chamber.

6. In a pump, a cylinder-cap provided with a valve-seat, a valve-cage carrying a check-valve to rest upon said seat, lifting-lugs provided at the upper portion of said valve-cage, a valved piston provided with hooks to engage said lugs by a rotation of the piston, a water-chamber

ber provided in said cylinder-cap above said valve-seat, a supporting-flange for said cage at the upper portion of said chamber, a bearing-stem extending upward from said check-valve, a centrally-disposed bearing for said stem at the lower portion of said cage, and a packing-ring carried by said cage.

7. In a pump, a piston-frame having a bearing-seat upon its upper face, a hub of less length than the frame within said frame and connected to said seat by radiating spokes having exteriorly-threaded faces, a threaded ring at the lower portion of said spokes, packings secured upon the periphery of said spokes, and a slidingly-mounted valve adapted to seat upon said frame and provided with an outwardly-curved under face.

8. In a pump, a piston-frame having a bearing-seat upon its upper face, a hub connected to said seat by radiating spokes having exteriorly-threaded faces, a threaded ring at the lower portion of said spokes, packings secured upon the periphery of said spokes, an apertured valve adapted to engage the seat upon said frame, a post extending upward from said valve, and a disk slidingly mounted upon said post to control the apertures in said valve.

9. In a pump, a piston-frame having a bearing-seat upon its upper face, a hub connected to said seat by radiating spokes having ex-

teriorly-threaded faces, a threaded ring at the lower portion of said spokes, packings secured upon the periphery of said spokes, an apertured valve adapted to engage the seat upon said frame, a post extending upward from said valve, a disk slidingly mounted upon said post to control the apertures in said valve, a check-valve cage disposed beneath said piston-frame and provided with oppositely-disposed lifting-lugs at its upper portion, and oppositely-disposed hooks carried by said frame to engage said lugs.

10. In a pump, a cylinder-cap provided with a valve-seat, a valve-cage carrying a check-valve to coöperate with said seat, and a series of segmental springs secured at one end to the cage and having their free ends disposed beneath the secured ends of the adjacent springs.

11. In a pump, a packing comprising a series of segmental springs secured at one end and having reduced free ends disposed behind the secured ends of adjacent springs and between the securing means therefor.

In testimony whereof I affix my signature in presence of two witnesses.

SAMUEL M. FULTON.
